Application February 6, 1941, Serial No. 377,693

8 Claims.

(CL. 68—12)

This invention relates to laundry machines, and more particularly to an improved machine wherein washing, rinsing and extracting operations may be performed upon a batch of clothing in a single container, without manual manipulation of the clothing during these operations. The machine preferably is provided with a timing and control mechanism for starting and stopping the various operations in a predetermined sequence.

It is among the objects of the present invention to provide a laundry machine capable of efficiently and economically performing the aforementioned operations with the use of a minimum volume of water.

A further object of the present invention is to provide in a laundry machine a single container adapted to be oscillated or linearly reciprocated for washing and rinsing purposes, and to be rotated for extracting purposes.

Another object of the invention is to provide in a laundry machine an extracting container mounted on a rotating shaft and wherein a reciprocating force is employed to overcome the tendency of the container to precess as it is rotated through its critical speed under the influence of an out-of-balance load, both in acceleration and deceleration or retardation.

A further object of the present invention is to provide in a laundry machine a container mounted on a rotating shaft and mechanism for applying a reciprocating force transversely of the axis of rotation of the container to correct precessional tendencies of the container while under rotative movement.

A further object of the present invention is to provide in a laundry machine a container mounted on a rotating shaft and mechanism for applying a reciprocating force transversely of the axis of rotation of the container to correct precessional tendencies of the container while under rotative movement, and timing mechanism for controlling the sequence of operation of said mechanism.

Another object of this invention is to provide in a laundry machine a combined washing and rinsing and extracting container carried on a shaft mounted for gyratory movement, mechanism for oscillating the shaft about its support to wash clothing in the container, and other mechanism for rotating the shaft for extracting purposes.

Another object of the present invention is to provide in a laundry machine a container carried on a shaft mounted for pivotal and rotary movement, and mechanism for simultaneously

applying a reciprocating force and torque to said shaft.

Briefly, this invention relates to a laundry machine embodying a tub having a shaft upon which is mounted a combined washing, rinsing and extracting container adapted to receive clothing and other objects to be washed. The container is oscillated for carrying out washing and rinsing operations and rotated or whirled for extracting operations with a minimum of wobbling or precession. The washing and extracting container is supported on the upper end of a vertical drive shaft which is mounted within a housing pivoted to the base of the machine. During the washing operation, the housing is caused to be oscillated or rocked about its pivotal support, and the displacement thus effected subjects the clothing disposed within the container to a rubbing and scrubbing action against suitable ribs formed on the inner surface thereof. Upon completion of the washing period, it is found that the clothing is not properly centered providing an out-of-balance load within the container, with the result that if the container should be spun in this condition, it would be subjected to violent vibration or precession, as it was accelerated through its critical speed.

It was found that if the oscillation or reciprocation of the tub was continued during acceleration and deceleration of the rotative movement through the critical speed, the tendency of the tub to wobble or vibrate excessively was minimized. It was found that a reciprocating force applied radially to the spinning container reacts with the torque applied to the drive shaft to maintain the container in substantially stable equilibrium until it has been accelerated to a point above the critical speed. Similarly, this force may be applied as the rotative movement of the container is retarded through the critical speed to a point of rest.

In applying this discovery to the operation of the present machine, the oscillation of the tub for the washing period is continued during the initial stages of rotation of the first extracting period and until the rotating speed thereof has reached a point that the container is in stable equilibrium. Just prior to the completion of the extracting period, oscillation of the container is again initiated and the spinning retarded through the critical speed to a point of rest. Rinsing water is applied to the clothing during the latter part of the extracting period to provide a whirling rinse which is continued as the rotation of the extractor decreases, and to provide a wash

rinse during the succeeding oscillating period. The oscillation is continued into the succeeding extracting period until the container has reached a predetermined rotary speed. In the operation of the machine, the oscillating and spinning periods overlap each other.

The foregoing and other objects of the invention will become more apparent and better understood after consideration has been given to the following detailed description taken in conjunction with the accompanying drawings, wherein like reference characters denote corresponding parts and wherein:

Figure 1 is a fragmentary sectional view through laundry apparatus constructed according to my invention, taken generally on the line 1-1 of Figure 2 and embodying a combined washing and extracting container.

Figure 2 is a sectional view taken on the line 2-2 of Figure 1 with parts thereof broken away to illustrate the drive for the reciprocating mechanism for the combined washing and extracting container;

Figure 3 is an enlarged sectional detail taken on the line 3-3 of Figure 1;

Figure 13 is an enlarged fragmentary side elevational view of the elements of the timing mechanism positioned as shown in Figure 11;

Figure 14 is a sectional view taken on the line 14-14 of Figure 8;

Figure 15 is a sectional view taken on line 15-15 of Figure 8;

Figure 16 is a plan view of the dial and indicating handle for the timing and control mechanism.

With reference to the accompanying drawings and particularly to Figures 1 and 2, the present invention is directed to a laundry machine including a substantially rectangular casing 10 suitably secured to and supported by the depending flange 11 of a base plate 12. The plate 12 may be supported in any suitable manner, as for example, by cushion elements 13 illustrated in Figure 1. The casing 10 is provided with a top 14 having a centrally disposed flanged opening 15 therein, affording access to the inside of the casing in which there is mounted a shell 16. Formed integrally with the top 14 at one side of the opening 15 are a pair of spaced hinge lugs 17 (see Figure 5), adapted to rotatably receive therebetween a hinge member 18 attached to a closure or lid 20 for the opening 15. The hinge

member 18 is provided with a duct 19 suitably closed at one end by the hinge pin 18a, and the other is provided with hinge tube 18b. Leading from the duct 19 and terminating in a down-turned nozzle adjacent the central part of the opening 15 is a conduit 21 which serves to direct a spray of water into a container positioned within the shell 16.

For supplying water to the machine, one end of an intake conduit 22 may be connected to a source of water supply, and the other end to the intake port of a control valve 23 (see Figure 7). The valve 23 controls the flow of water to the spray nozzle projecting into the casing. The valve 23 comprises a valve member 25 mounted on the valve stem 26, which is adapted to be actuated by the timing and control mechanism hereinafter described. In the conduit 24, there is provided a regulating needle valve 27 which is manually controlled by a lever 28 on the upper portion of the casing 10, which lever has a dial 29 associated therewith. The valve 27 serves to regulate the volume of water flowing through the conduit 24 and to compensate for different pressures on the supply line so that when the valve 23 is opened for a predetermined period, a definite volume of water will be introduced into the container positioned within the casing.

The shell 16 is formed with a wall portion 30 which is substantially oval in cross-section, having an inwardly extending trough 31 formed on the lower edge thereof. The bottom 32 of the trough is downwardly inclined and terminates in an outlet 33 which may be connected by a conduit 34 to a suitable drain. The shell 16 is supported on angles 35 secured to the inner wall of the casing 10.

Disposed within the shell 16 is a combined washing and rinsing and extracting container 36, which is generally spherical in contour having a flanged opening 37 in the top thereof, through which clothing and washing fluid are introduced into the container. Mounted on the lower inner surface of the container are suitable washing projections 38 against which the clothing is adapted to be rubbed and scrubbed during the washing operation. Extending through the wall of the container at the line of greatest diameter are a plurality of small apertures 39 disposed in a ring about the container and through which fluid is adapted to be expelled from the container by centrifugal force upon rotation of the container. The apertures 39 are normally sealed by a resilient band 40 mounted on the exterior surface of the container and maintained in position by angular members 41. Spaced springs 42 tighten the band to seal the openings until centrifugal force counteracts the spring tension and releases the fluid through the openings 39. An inclined drip rim 43 secured to the outer surface of the container below the apertures 39 directs fluid flowing therefrom into the trough 31.

The container 36 is secured to the upper surface of a plate 44 formed on the end of a drive shaft 45 rotatably mounted within a tubular housing 46. The lower end of the housing is supported by a yoke 47, the ends of which are pivotally connected to spaced bracket members 48 mounted on the base plate 12. Suitable resilient pads 49 are disposed between the base of the bracket members 48 and base plate 12 to provide a resilient support for the housing 46. On the shaft 45 between the upper end of

the housing 46 and the lower surface of the plate 44 are positioned roller bearing 58 and a coupling member 51. For facilitating the oscillating movement of the container, there is provided a plurality of longitudinally extending coil springs 52 extending radially from a ring 53 encircling the upper end of the housing 46 to bracket members 54 secured to the inner walls of the casing 10. These springs serve to urge the return of the container at the end of each reciprocating stroke. Transverse springs 52a co-operate with springs 52 to maintain the container in equilibrium during the extracting operation.

The lower end of the drive shaft 45 extends below the housing 46 and has freely rotatable thereon a pulley wheel 55 which is maintained thereon by means of a thrust bearing 56 and a nut 57. Slidably splined to the shaft 45 between the pulley 55 and the end of housing 46 is a drum 58 having a friction shoe 59 on the lower surface thereof and engageable with the face of the pulley 55. The drum is normally urged into engagement with the pulley wheel 55 by means of a coil spring 60 encircling the shaft 45 between the hub of the drum 58 and the end of the shaft housing 46, to effect a driving connection between pulley 55 and shaft 45 for rotating the latter. The drum 58 is provided with an outwardly extending flange 61 having a friction shoe 62 secured to the lower surface thereof. A drum 63 encircling the drum 58 is formed with an inturned flange 64 against which the friction shoe 62 bears when it is desired to retard the rotation of the shaft 45 and to disengage the shaft from the pulley 55. The drum 63 which serves to move the drum 58 along the shaft 45 against the force of the spring 60 is actuated by a disc 65 formed with a central sleeve 66 which encircles the lower end of the housing 46. The disc 65 is supported on the lower ends of links 67 which are pivoted to the ends of the crank arms 68 mounted on the rod 69 which is journaled in a suitable bearing formed on the yoke 41. Rotative movement is imparted to the rod 69 by a lever 70 adapted to be actuated by a wire 71 leading from the timing and control mechanism of the machine to be hereinafter described.

For washing clothing, the container 36 is oscillated within the shell 16 by applying a reciprocating force to the upper end of the shaft 45 to rock or oscillate the shaft about its pivotal support. This movement is carried out by suitable driving mechanism 72 which through associated linkage serves to reciprocate the shaft 45 about the pivots 48. This mechanism (see Figure 1) comprises a casing 73 supported in a bracket 74 mounted on the base plate 12. Disposed within the casing 73 is a vertical drive shaft 75 which extends downwardly through the wall of the casing and has mounted thereon a pulley wheel 76. The upper end of the shaft 75 carries a pinion 77 which is adapted to mesh with a gear wheel 78 freely rotatable on the lower end of a shaft 79. The upper surface of the gear wheel 78 is provided with a diametrically extending slot 80 which is adapted to receive a pin 81 extending through the lower end of the shaft 79. The gear wheel 78 is slidably 70 in mesh with the pinion 77 and rotates continuously during the operation of the machine, and the shaft 79 is operatively connected to the gear wheel 78 by bringing the slot 80 into engagement with the pin 81. For shifting the gear 75

wheel longitudinally of the shaft, there is provided a yoke 82 engageable with an extension 83 formed on a cap 84 threaded on the hub of the gear wheel 78. The yoke 82 is actuated by 5 means of a rod 85 having a crank arm 86 on its outer end which is operatively connected to the timing mechanism by wire 86a. A spring 87 encircling the rod 85 normally urges the yoke 82 upwardly to engage the gear wheel and shaft 10 79.

The shaft 79 is journaled in an upwardly extending housing 88 formed integrally with the gear case 73. A bracket 89 extending from the housing 88 to the wall of the casing 10 serves to 15 support the upper end of the housing 88. Formed on the upper end of the shaft 79 is a crank arm 90 which has associated therewith a universal coupling member 91. A connecting rod 92 extends between the coupling member 91 on the 20 shaft 79 and the coupling 91 on the crank 90. A spring 93 extending transversely from the end of connecting rod 92 to the wall of the casing 10 serves to urge the crank arm out of alignment with the shafts 79 and 45 to permit longitudinal 25 free movement of the connecting rod 92. A spring pressed pawl 94 (see Figure 4) mounted on the connecting rod 92 and engageable with a rack 95 formed on the lower surface of the plate 44 effects a step by step rotation of the container 36 30 during the linear reciprocation thereof. This rotative movement of the container changes the position of the clothing therein with respect to the path of reciprocation, so that all of the clothing within the container may be uniformly washed.

The pulley wheel 55 on the shaft 45 and the pulley wheel 76 of the reciprocating mechanism are operatively connected by means of a belt 96 to the driving pulley 97 mounted on the lower 40 end of the armature shaft of a motor 98. Motor 98 is pivotally mounted in a bracket 99 secured to the wall of the casing 10, and the belt 96 is tensioned by a spring 100 extending between the motor 98 and a bracket secured to the casing wall.

With reference to Figures 8 to 16, inclusive, there is illustrated timing mechanism for controlling the actuation of the container 36 within the shell 16 and the supply of water thereto through the valve 23. Journaled in the gear case 50 13 (see Figure 1), is a shaft 101 having a worm wheel 102 attached to the inner end thereof and adapted to engage a worm 103 formed on the drive shaft 75. The outer end of the shaft 101 has universally connected thereto a connecting rod 104 serving to connect worm 102 for driving the timing and control mechanism which is suitably supported between spaced bracket members 105. On one side of the bearing plates 105 are formed aligned upstanding ears 106 between which is mounted an elongated actuating cam 108 which is adapted to be rotated in a counter-clockwise direction, and supported at each end on stub shafts 107. One of the shafts 107 is connected to the end of the driving rod 104 by means of the swivel joint 109. Mounted on a shaft 110 which is supported in the bearing plates 105 are a series of ratchets and cam discs for timing and controlling the sequence of operation of the various washing steps carried out in the container 36.

Attached to and driven by an eccentric 111 mounted on the shaft 107 is a rod 112 which actuates a pawl 113 (see Figure 14), supported on the upper end of an arm 114. The pawl 113 serves to rotate a ratchet wheel 115 on the shaft 110,

which is operatively connected to disc 116 having a single notch in the periphery thereof. Associated with the pawl 113 for movement therewith is a second pawl 117 which normally rides on the peripheral surface of the disc 116 and is adapted to engage the teeth of a second ratchet wheel 118 and rotate the same the distance of one tooth upon each rotation of the disc 116.

Attached to the ratchet wheel 118 for rotative movement therewith is another ratchet wheel 119 with the teeth thereof extending in a reverse direction. Ratchet wheel 118 and disc 116 and ratchet wheels 118 and 119 rotate as pairs freely upon the shaft 110. Adjacent the ratchet wheel 119 is a disc 120 supporting a pawl 121 adapted to engage and be driven by the ratchet wheel 119. The disc 120 together with a group of cam disc elements 122, 123, 124, 125, 126 and 127 are keyed on a sleeve 128 to rotate as a unit about the shaft 110. The sleeve 128 extends through the bearing plates 105 and has mounted thereon a sprocket wheel 129. The sprocket wheel 129 by means of a chain 130 and a second sprocket 131, is connected to the indicating lever 132 associated with an indicating dial 133 (see Figure 16) mounted on the upper portion of the side wall of the casing 10. The sleeve 128 and cam disc elements carried thereby are rotated by the mechanism once in twenty-four minutes, which constitutes a complete cycle of operation, as indicated on the dial 133 of Figure 16. The cam disc elements 123 and 122 serve to control the starting and stopping of the mechanism for oscillating the container 36; the discs 124 and 125 similarly control the mechanism for rotating the container for extracting operations, and discs 126 and 127 control the operation of the valve 23 regulating the flow of water into the container. The foregoing pairs of control discs are substantially similar, differing only in the relative positions of the cam notches formed in the peripheries thereof. Furthermore, the sets of levers which are actuated by each pair of discs are similar and accordingly for purposes of brevity and simplification, only one set of levers will be described herein.

In Figures 10, 11 and 12, there is disclosed the three positions of the levers actuated by any one pair of cam discs. With reference to these figures, the control levers comprise a toggle arm 134 pivotally mounted on a shaft 135 extending between the bearing plates 105. An elongated slot 136 through which extends a rod 137 supported between the bearing plates defines the extent of movement of the toggle arm 134. Pivot to the toggle 134 as at 139 are a pair of arms 140 and 141 which extend over their associated control discs, and are connected to operate together by means of a spring 142. The arm 140 is provided with a finger 143 which normally rides on the peripheral surface of its associated disc and drops within the notches formed therein as the discs are slowly rotated into position. The arm 141 is formed with a finger 144 which, when the finger 143 drops into a notch, is lowered into position to be engaged by the rotating cam shaft 108. The cam shaft 108, which is rotating in a counter-clockwise direction pulls the arm 141 into the position shown in dotted lines in Figure 11, and moves the toggle arm 134 from the position shown in Figure 10 to that shown in Figure 11. The arms 140 and 141 are normally urged into actuating position with respect to the timing disc and cam shaft 108 by means of a spring 145 extending from the arm 141 about a spacer disc 146 on the shaft 110, and anchored to a rod 147 75

extending between the bearing plates 105. The spring 145 also serves to return the arms 140 and 141 to the position shown in Figure 10. When the toggle arm 134 is shifted into the position illustrated in Figure 11, a pawl 148 pivotally mounted on a rod 149 is caused to engage a notch in the lower surface of the toggle arm 134, and maintain it in its extended position. Associated with the pawl 148 is an arm 150 having one end pivoted to the rod 149 extending between plates 105, and the other end formed with a finger 151 adapted to ride on and drop into notches formed in the periphery of a timing disc. The pawl 148 and arm 150 are operatively connected together by means of a spring which maintains a pin 152 in engagement with the edge surface of arm 150. A tensioned spring 153 extending between the arm 150 and the rod 147 serves to maintain the finger 151 in engagement with the periphery of the disc 125. When the finger 151 drops in one of the notches of its associated disc, the pawl 148 is disengaged from the toggle arm 134 by the pin 152, permitting the toggle arm to return to its initial position, as illustrated in Figure 12.

25 Mounted on the sleeve 128 is a cam element 154 controlling a segment arm 155, which actuates a three way snap switch 156. The switch 156 serves to open the electric circuit to the motor 98 upon the completion of a cycle of operation of the machine. A manually operated three way toggle switch 157 on the wall of the casing below the dial 133 is interconnected with the switch 156 to control the motor circuit, so that after the circuit is manually closed by switch 157, it may be automatically opened by switch 156.

30 In the operation of the laundry machine of the present invention, the supply conduit 22 is connected to any suitable water supply under pressure and at the desired temperature, and the outlet 33 of the tub 16 is connected to a suitable drain by means of the conduit 34. The electric conduit for conveying current to the motor 98 is connected to a source of current supply.

35 Clothing and soap are placed in the container 36 and lid 20 is closed, and then the switch 157 is actuated to close the circuit to the motor 98. Simultaneously with the starting of the motor, the timing and control mechanism is initiated. The cam disc 126 of the timing mechanism controlling the water supply to the machine opens the valve 23 and water flows through the valve 27 and conduit 21 into the container 36. The timing mechanism maintains the valve 23 open for a period of about one and one-fourth minutes, as indicated on the dial 133, during which time a predetermined amount of water flows into the container. The operator adjusts the needle valve 21 so that the flow of water into the container will conform to the pressure of the supply line and the correct volume of water will pass into the container during the stated period. While the water is flowing into the container, the time control disc 123 through its associated toggle member 134 pulls the wire 86 rotating the arm 86 which actuates the toggle 82 to move the gear wheel 78 along the shaft 79 into engagement with the pin 81, thereby connecting the shaft 78 to the drive shaft 75. The shaft 78 through its associated crank arm 90 and connecting rod 92 oscillates the container 36 for a period of nine minutes during which time the clothing is washed. Upon each reciprocation of the container 36, the pawl 94 on the connecting rod 92 is effective to rotate the container one notch on the rack 95, thereby continually shifting the clothes within

the container with respect to the direction of reciprocation. About one-fourth minute prior to the expiration of the washing period, the timing disc 124 shifts its associated toggle arm 134 which is connected to wire 11. The force thus applied to wire 11 is effective to operatively connect the pulley wheel 55 to shaft 45 for rotating the container. The oscillation of the container 38 is continued during the acceleration of the rotating speed of the container and until it has reached a speed where the container is in equilibrium and not subject to any tendency to wobble or precess, at which time cam disc 122 is effective to terminate the oscillating period by disengaging the gear wheel 78 and shaft 79. During the spinning of the container, the washing fluid is extracted from the clothing and passes out of the container through the openings 39, the band 40 unseating the openings under the centrifugal force of the fluid in the spinning container. Just prior to the termination of the extracting period of the container, the oscillation of the container is again initiated and is continued during the deceleration of the container. It is intended in this invention to use a reciprocating force to overcome the tendency of the container to precess as it is rotated through its critical speed both in acceleration and deceleration. During the latter part of the first extracting period, the timing mechanism opens the valve 23 to permit the spray of rinse water to pass through the clothing while rotating at high speed. The valve remains open into the succeeding oscillating period. The clothing disposed within the container is subjected to oscillation for a wash rinse for a period of two and one-half minutes, after which it is extracted. The rinsing and extracting operations are again repeated as indicated on the dial 133, and then the container is subjected to a final drying period at the conclusion of which the container is oscillated to bring the same to a stop through its critical period. At the end of the twenty-four minute cycle, the machine is automatically shut off by the switch 156. It will be seen that the oscillating and rotating periods of the container overlap so that the container is rapidly oscillated during acceleration and deceleration of the container.

Having thus described my invention, what I desire to obtain by Letters Patent is defined by the appended claims.

What I claim is:

1. In a laundry device of the class described, an upstanding pivotally mounted housing supported for gyratory movement, a shaft journaled in said housing, a combined washing and extracting container mounted on said shaft, means including a connecting rod for oscillating said shaft in a plane for washing clothes within said container, means for rotating said shaft and the container supported thereby for extracting purposes, and means for permitting the free movement of said connecting rod with said rotating shaft upon cessation of the oscillating means.

2. In a laundry device of the class described, a casing, a combined washing and extracting container, a shaft mounted for gyratory movement within said casing and supporting said container on one end thereof, means for rotating said shaft and spinning the container supported thereby, means for applying a reciprocating force perpendicular to the axis of rotation of said shaft during acceleration and retardation thereof to prevent precessional movement of said container under torque.

3. A laundry machine of the class described comprising a casing, a combined washing and extracting container, an upstanding pivotally mounted housing, a shaft journaled in said housing and supporting said container on the upper end thereof, said shaft and container being mounted so as to permit gyratory movement thereof, means for linearly oscillating said shaft about its pivotal support for washing clothing in said container, means for rotating said container to extract water from clothing disposed in said container, and control means for sequentially operating said oscillating means and rotating means in such a manner as to overlap the oscillating and rotating movement of the container to correct precessional tendencies of said container.

4. A washing machine comprising a container for clothes and washing fluid secured to a shaft, said shaft mounted for free rocking movement in one plane and resiliently restrained against substantial rocking movement in a plane transverse to said first plane, power means to rotate said container and shaft on its axis to effect centrifugal extraction, means to rock said container in said first-named plane to effect a washing of the clothes in the container, control means arranged to operate said last-named means during the initiation of the centrifugal extraction operation and during the last portion of the centrifugal extraction operation, whereby the gyration of said shaft due to out-of-balance load in the container is opposed.

5. In a combined washer and extractor, a clothes container means for rocking the container in one plane to effect washing and means to rotate the container at a high speed in a plane normal to said first plane to effect extraction, mechanism to counteract and prevent excessive gyration of the container when the basket is being rotated through a critical speed occasioned by an out-of-balance load, comprising means to rock said basket in said first-named plane during said critical speed.

6. A washing machine comprising a container provided with a depending shaft, said shaft mounted for rotation upon its axis to effect extraction and supported for pivotal movement adjacent its lower end on an axis transverse to the shaft axis, means to rotate the shaft and container means to oscillate said shaft about its pivotal support to effect washing of the clothes and to restrain excessive gyration of said shaft and basket during that phase of the extraction operation when the container is rotating through a critical speed occasioned by an out-of-balance load.

7. A laundry machine comprising a container for clothes and washing fluid, a vertically extending shaft supporting said container, means to rotate said shaft to effect centrifugal extraction, means to rock said shaft and container in a single plane to effect washing, said last-named means including a sleeve surrounding said shaft and freely rotatable thereon, connecting rod secured to the sleeve at one end and operatively connected to a rotating eccentric at the other end, power means operatively connected to a means for rotating the shaft to effect extraction and the rotating eccentric, said rotating eccentric and connecting rod being effective during the extracting phase of the machine operation to reduce the amplitude of precession.

8. A washing machine comprising a container

for clothes and washing fluid secured to the upper end of a shaft, said shaft mounted for free rocking movement in one plane and restrained against substantial rocking movement in a plane transverse to said one plane, means to rotate said container at a high speed to effect extraction and means to rock said container

in said one plane, said two last-named means being operatively connected to each other so that the acceleration and deceleration of the rocking movements corresponds to the acceleration and deceleration of the rotational movement.

JAMES B. KIRBY.
